CERTAIN BENZIMIDAZOLIUM COMPOUNDS SUBSTITUTED IN THE 1,2,3-POSITIONS

Christian Wiegand and Wolfgang Wirth, both % Farbenfabriken Bayer, A.G., Wuppertal-Elberfeld, Germany

No Drawing. Filed Jan. 27, 1959, Ser. No. 789,239

Claims priority, application Germany Jan. 29, 1958

6 Claims. (Cl. 260—309.2)

This invention relates to novel chemical compounds useful in chemotherapy and more particularly it is concerned with certain novel benzimidazoles that are useful in altering blood pressure.

It is known that certain compounds such as epinephrine and the sympathomimetic amines are effective agents for increasing blood pressure. However, they have the disadvantage of being highly toxic materials and also of being substances toward which many persons exhibit idiosyncratic reactions. Furthermore, the use of these agents in cases of chronic hypotension has been found to result in the development of a tolerance and thus a need has been felt for other agents that might be employed in treatment of hypotension which might have the advantages of reduced toxicity, prolonged action, strong vasoconstrictor effects and reduced incidence of idiosyncratic reactions.

Various agents for reducing blood pressure have long been known, notably nitroglycerin, nicotinic alcohol derivatives, reserpine, priscoline and ganglionic blocking agents. Nitroglycerin has the disadvantage of rapidly producing an effect which is not sustained; the nicotinic alcohol derivatives and reserpine are disadvantageous for a variety of reasons, and the ganglionic blocking agents are much too dangerous for use except under carefully supervised conditions, such as in a hospital.

It is known that certain derivatives of imidazole, when administered, produce marked effects on the blood pressure. Thus, 2-benzyl-3,4-dihydroimidazole produces strong vasodilator effects, whereas, in contrast, 2-(α -naphthylmethyl)-3,4-dihydroimidazole is a potent vasoconstrictor. It has been considered in the prior art that replacement of the alkyl or aralkyl groups in the 2-position by an aryl or heterocyclic radical would lead to compounds having practically no effect on the blood pressure.

The surprising discovery is now made that compounds which raise the blood pressure considerably and for prolonged periods can be obtained by producing benzimidazolium compounds of the following general formula:

In the above formula, R₁ represents an unsaturated short-chain aliphatic radical, for example allyl, methallyl, haloallyl, or crotyl, while R₂ and R₃ stand for identical or different aryl, aralkyl, heteroaryl, and heteroaralkyl radicals, which may be substituted in turn. X is a non-toxic anion. It will be understood that the benzene nucleus of the benzimidazole moiety may be substituted by one or more monovalent substituents such as halogen, alkyl, alkoxy, acylsulfonyl, sulfonamido, nitro, or amino groups.

2

Even in small doses these compounds show a pronounced and sustained elevating effect on the blood pressure. A pressure increase lasting several hours, for instance, is produced in the narcotized cat by administration of only one to two milligrams of a representative compound of the group.

Various methods for preparing the benzimidazolium compounds according to this invention are available. Compounds of the type, for example:

may be reacted with reactive esters of unsaturated aliphatic alcohols, for instance, with esters of hydrohalic acids or esters of alkylsulfonic and arylsulfonic acids; or compounds of the type:

may be subjected to the action of reactive esters of hydroxymethylaryl or hydroxymethyl heteroaryl compounds. As an example of the first reaction, the known 1-benzyl-2-phenylbenzimidazole may be reacted with allyl bromide and, furthermore, 1-allyl-2-phenylbenzimidazole may be reacted with benzyl chloride.

Alternatively, compounds of the type

may be reacted with arylcarboxylic acids, aralkylcarboxylic acids, heteroarylcarboxylic acids, or heteroaralkylcarboxylic acids, or with reactive acid derivatives thereof followed by closure of the benzimidazole ring by conventional methods.

To facilitate a fuller and more complete understanding of the subject matter of this invention, certain specific examples herewith follow but it is clearly to be understood that these examples are provided by way of illustration merely and are not to be construed as imposing limitations upon the scope of the invention defined in the subjoined claims.

Example I

55 2-benzyl-benzimidazole is heated in the presence of an aliquot amount of sodium ethoxide with a small excess of crotyl chloride, the sodium chloride formed is removed by vacuum filtration, and the residue is evaporated, then dissolved and reprecipitated from dioxane to give 60 1-crotyl-2-benzyl-benzimidazole, melting at 205°-208° C. Administration of the product causes raising of the blood pressure.

Example II

65 2-benzyl-benzimidazole is heated with slightly more than 2 moles of allyl bromide in the presence of 1 mole of sodium ethoxide, then the mixture is worked-up as described in Example I and the product is reprecipitated from methanol to give 1,3-diallyl-2-benzyl-benzimidazolium chloride, melting at 277°-278° C. Administration of the product causes raising of the blood pressure.

Example III

1-(β -methylallyl)-2-benzyl-benzimidazole is prepared from β -methylallyl chloride and 2-benzyl-benzimidazole by heating these reactants together with sodium ethoxide in a procedure according to Example I. The hydrochloride of this compound is found to melt at 118°-120° C., following reprecipitation from acetone. This compound is heated for a short time under reflux with twice the stoichiometrically equivalent amount of allyl bromide and, after boiling for about 1 hour, the liquid solidifies. After grinding with ethyl acetate and redissolution in isopropanol, 1-(β -methylallyl)-2-benzyl-3-allyl-benzimidazolium chloride is obtained melting at 265°-267° C. with decomposition. Administration of the product causes raising of the blood pressure.

Example IV

2-(α -hydroxybenzyl)-benzimidazole is heated for several hours with a small excess of crotyl chloride in the presence of the calculated amount of sodium ethoxide and the precipitated sodium chloride is filtered off under suction. 1 - crotyl - 2 - (α - hydroxybenzyl) - benzimidazole crystallizes upon cooling and when it has been recrystallized from absolute alcohol, it melts at 162°-163° C. Administration of this product causes lowering of the blood pressure.

Example V

About 18.4 grams of 2-(2'-furyl)-benzimidazole is heated under reflux with 15 grams of allyl bromide in sodium ethoxide solution produced by reacting 2.3 grams of sodium and 100 cubic centimeters of absolute ethanol for 4 hours. The residue remaining after separation of precipitated sodium bromide is fractionated in vacuo. The resultant 1-allyl-2-(2'-furyl)-benzimidazole distills as a nearly colorless oil at a constant boiling point of about 180° C. under a pressure of 3 millimeters of mercury. It solidifies to a colorless crystal mass that melts at 65°-67° C. Upon administration, this product causes a rise in blood pressure.

Example VI

About 1 part by weight of 2-phenyl-1-benzyl-benzimidazole (melting point, 136°-137° C.) is heated, under reflux, with 2½ parts by weight of allyl bromide. Precipitation of 1-allyl-2-phenyl-3-benzyl-benzimidazolium bromide begins after a short time. Following evaporation of excess allyl bromide and redissolution in isopropyl alcohol, colorless crystals, melting at 184°-186° C., are obtained. Upon administration, this product causes a rise in blood pressure.

Example VII

Approximately equal parts by weight of 1-allyl-2-(2'-furyl)-benzimidazole (which may be prepared according to Example V) and of 2-thienylmethyl chloride are heated together to about 100° C. for several hours. The mass begins to solidify in about 1 hour. Following re-

dissolution in a mixture of isopropyl alcohol and ethyl acetate, fine, colorless crystals of 1-allyl-2-(2'-furyl)-3-(2'-thienylmethyl)-benzimidazolium chloride are obtained which melt with decomposition at 191°-193° C. and which are readily soluble in water. Upon administration, this product causes a rise in blood pressure.

Example VIII

Approximately equal parts by weight of 2-thienylmethyl chloride and 1-allyl-2-phenylbenzimidazole (melting point 95°-96° C.), which may be prepared according to the method of Example V using 2-phenylbenzimidazole as a starting material, are heated together on a water bath in the absence of moisture for about 1 hour, whereupon the entire mass crystallizes. Recrystallization from a mixture of a small amount of isopropyl alcohol and acetone yields 1-allyl-2-phenyl-3-(2'-thienylmethyl)-benzimidazolium chloride, melting at 215°-216° C. (with decomposition), which dissolves in water. Upon administration, this product causes a rise in blood pressure.

Example IX

Approximately equal parts by weight of 4-chlorobenzyl chloride and 1-allyl-2-phenylbenzimidazole (melting point 95°-96° C.), which may be prepared from 2-phenylbenzimidazole by the method according to Example V, are heated on a water bath. During 1 hour, the entire mass solidifies in crystalline form. After grinding with ethyl acetate and reprecipitation from chloroform by addition of carbon tetrachloride, fine, colorless needles of 1-allyl-2-phenyl-3-(4'-chlorobenzyl)-benzimidazolium chloride, melting at 223°-225° C. are obtained, which are very easily water-soluble. Upon administration, this product causes a rise in blood pressure.

Having thus described the subject matter of this invention, what it is desired to secure by Letters Patent of the United States is:

1. 1,3-diallyl-2-benzyl-benzimidazolium bromide.
2. 1 - (β - methylallyl) - 2 - benzyl - 3 - allyl - benzimidazolium chloride.
3. 1-allyl-2-phenyl-3-benzyl-benzimidazolium bromide.
4. 1 - allyl - 2 - (2' - furyl) - 3 - (2' - thienylmethyl)-benzimidazolium chloride.
5. 1 - allyl - 2 - phenyl - 3 - (2' - thienylmethyl)-benzimidazolium chloride.
6. A benzimidazolium compound selected from the group consisting of 1,3-diallyl-2-benzyl-benzimidazolium bromide, 1 - (β - methylallyl) - 2 - benzyl - 3 - allyl-benzimidazolium chloride, 1-allyl-2-phenyl-3-benzyl-benzimidazolium bromide, 1-allyl-2-(2'-furyl)-3-(2'-thienylmethyl)-benzimidazolium chloride and 1-allyl-2-phenyl-3-(2'-thienylmethyl)-benzimidazolium chloride.
